Liu, D., "Marker," U.S. Appl. No. 29/394,219, filed Jun. 14, 2011.

* cited by examiner

Primary Examiner — Elizabeth Albert*(74) Attorney, Agent, or Firm* — Christensen O'Connor Johnson Kindness PLLC(57) **CLAIM**

The ornamental design for a marker, as shown and described.

DESCRIPTION

FIG. 1 is a lower front left perspective view of a marker showing my new design;

FIG. 2 is a front elevation view thereof;

FIG. 3 is a rear elevation view thereof;

FIG. 4 is a right side elevation view thereof, with the left side elevation view being a mirror image of the right side elevation view;

FIG. 5 is an enlarged top plan view thereof; and,

FIG. 6 is an enlarged bottom plan view thereof.

The broken lines shown in FIGS. 1 and 6 illustrate environmental subject matter and form no part of the claimed design.
